IGNITION APPARATUS

Victor A. Le Blanc, New Orleans, La., assignor
of one-twentieth to William H. Hartson, New
Orleans, La.

Application November 12, 1935, Serial No. 49,427

2 Claims. (Cl. 123—143)

This invention relates to an ignition apparatus for internal combustion engines, and has for the primary object the provision of a device of this character which eliminates electrical appliances, hot tubes, heaters of any kind and the mechanical injection of low grade fuels and thereby reduces fire hazards to a minimum and eliminates failure of igniting due to carbon, water shortage or unequal pressures in multiple cylinders and 5 provides an ignition which will assure igniting of improperly mixed fuels and permits the use of low grade fuels with an ordinary carburetor or mixing valve.

With these and other objects in view, this invention consists in certain novel features of construction and operation, combination and arrangement of parts to be hereinafter more fully described and claimed.

For a complete understanding of my invention, 20 reference is to be had to the following description and accompanying drawing, in which

Figure 1 is a transverse sectional view showing an internal combustion engine of the one cylinder four cycle type equipped with an ignition apparatus constructed in accordance with one type 25 of my invention.

Figure 2 is a fragmentary sectional view showing a cam employed for actuating an ignition valve at predetermined intervals.

Referring in detail to the drawing, the numeral 30 1 indicates a conventional type of internal combustion engine wherein the cylinder 2 is shown as mounted on a base 3 and equipped with a head 4 in which is formed an exhaust port or passage 5 controlled by an exhaust valve 6. The exhaust valve 6 is actuated by a valve mechanism 7. The valve mechanism 7 receives its motion by a cam (not shown) mounted on a cam shaft 8 journaled in the base 3 and geared to a 35 crank shaft 9. A piston 10 reciprocates in the cylinder 2 and is connected to the crank of the crank shaft 9, by a connecting rod 11. The intake port for the cylinder 2 is indicated by the character 12.

The type of engine described operates on the four cycle principle and is of the conventional construction and to which my invention is adapted.

A head 13 is suitably mounted to the cylinder 2 and has a fuel passage 14 connected with the intake port 12 of the cylinder 2 and to an intake manifold 15, the latter being connected to a carburetor or mixing valve (not shown) and which may be of any conventional construction. An auxiliary cylinder 16 is suitably mounted to the

cylinder 2 and is connected to the head 13 and slidably in said auxiliary cylinder is a piston 17 having a stem 18 carrying a roller 19 which rides upon a cam 20 secured to the cam shaft 8. A valve cage 21 traverses the fuel passage 14 and communicates the latter with the cylinder 16. A valve 22 is associated with the valve cage 21 and controls the communication between the fuel passage 14 and the cylinder 16 and the stem 23 thereof engages with a valve actuating mechanism 24. The valve actuating mechanism 24 includes a roller 25 which rides on the cam 26 secured to the cam shaft 8.

The valve cage 21 has ports 27 through which gases pass that are drawn through fuel passage 14 on the intake stroke of piston 10 thereby cleaning burnt gases from cylinder 16, valve cage 21 and fuel passage 14 from previous combustion, also cooling all latter parts mentioned on compression stroke of piston 10 when gases are forced into ignition cylinder 16 at charging stroke of piston 17. Valve stem piston 28 is used to help close ignition valve 22 and as a compression sealing piston. A self seating intake valve 29 is arranged in the intake manifold 15 and is adapted to permit gases to pass into the fuel passage 14 from the carburetor or mixing valve (not shown) by the suction created by the piston 10 on its suction stroke and seals the gases in the fuel passage 14 on compression stroke of piston 10 which makes fuel passage 14 part of combustion chamber at that period of operation. Thus it will be seen how the cylinder 2 receives its charge of combustible gases from the main combustion chamber.

The cam 20 has high faces A and B and low faces C and D. The cam 26 has a high face E and a low face F.

In operation, the piston 10 when on its suction stroke draws gas from the carburetor or mixing valve (not shown) by way of the fuel passage 14, as the piston 10 completes part of its compression stroke, the gases drawn into the cylinder 2 is compressed and after the piston 10 has traveled approximately sixty percent of its compression stroke, the roller 19 of the piston 17 engages the low face C of the cam 20 allowing the piston 17 to lower in the auxiliary cylinder 16 which allows the compressed gases to enter the combustion chamber of the auxiliary cylinder 16 through valve cage ports 27 and valve 22 while said valve is held open by high face E of cam 26. At about 80 percent of compression stroke of piston 10 the valve 22 is closed by its roller 25 dropping in the low face F of cam 26 at which time the com-

pressed gases in the auxiliary cylinder 18 combustion chamber has a pressure of about 65 pounds. The piston 17 of the auxiliary cylinder 18 is raised by its roller 19 rising to the high 5 face B of cam 28 which is completed at about 95 percent of compression stroke of piston 10 which increases the pressure of gases in cylinder 18 to about 500 pounds pressure, which causes spontaneous combustion at which time valve 22 is 10 opened by its roller 25 rising to high face E of cam 28 allowing combustion flame of 600 pounds or more pressure with Fahrenheit temperature of over 1500 degrees to ignite gases in fuel passage 14 and cylinder 2 which then has been 15 fully compressed by piston 10 reaching the limit of its compression stroke, which starts it on its expansion stroke. While the piston 17 is held at the top of its compression stroke for about 10 percent of power or expansion stroke of piston 20 10 to allow full force of combustion flame to expel itself in fuel passage 14 then piston 17 with roller 19 is allowed to drop in low face D of cam 28 for cooling purposes and again raised to exhaust 25 through fuel passage 14 which is accomplished at about 85 percent of expansion stroke of piston 10 by its roller 19 rising to high face A of cam 28 and held in that position until the completion of exhaust stroke, suction stroke and 60 percent of compression stroke of piston 10 which completes 30 the cycles of operation.

The ignition valve 22 is held open for cooling purposes by high face E of cam 28 closing only for period of compression stroke of piston 17. The cylinders 18 and 2 as well as the head 4 are 35 suitably water jacketed.

An ignition apparatus of the character described will assure igniting of low grade fuels as well as improperly mixed fuels and eliminates electrical ignitions or other forms of ignition employing heaters and the like.

Having described the invention, I claim:

1. In combination with an internal combustion engine, a fuel compressing and firing cylinder mounted on said engine, a head for said cylinder and having a fuel passage connected at one end with the engine and connected at the other end with a fuel intake manifold, a cage mounted in said head and communicating with the cylinder and passing through the fuel passage and having ports aligning with said passage to permit fuel from one end of said passage to pass to the other end of said passage and to enter said cylinder, a valve mechanism controlling the communication of the cage with said cylinder and for controlling the ports of the cage, a timing mechanism for operating the valve mechanism and driven by the engine, and a piston driven by the engine and operating in the cylinder for compressing and firing fuel in said cylinder and thereby ignite fuel in the engine.

2. In combination with an internal combustion engine, a fuel compressing and firing cylinder mounted on said engine, a head for said cylinder and having a fuel passage connected at one end with the engine and connected at the other end with a fuel intake manifold, a cage mounted in said head and communicating with the cylinder and passing through the fuel passage and having ports aligning with said passage to permit fuel from one end of said passage to pass to the other end of said passage and to enter said cylinder, a valve mechanism controlling the communication of the cage with said cylinder and for controlling the ports of the cage, a timing mechanism for operating the valve mechanism and driven by the engine, a piston driven by the engine and operating in the cylinder for compressing and firing fuel in said cylinder and thereby ignite fuel in the engine, and a check valve for said fuel passage and located 20 between the cage and the fuel intake manifold.

VICTOR A. LE BLANC.
